DESIGN FOR A HOUSE DRESS

Evelyn W. Turner, Hollywood, Calif.

Application January 31, 1938, Serial No. 74,750

Term of patent 3½ years

To all whom it may concern:

Be it known that I, Evelyn W. Turner, a citizen of the United States, residing at Hollywood, in the county of Los Angeles and State of California, have invented a new, original, and ornamental Design for a House Dress, of which the following is a specification, reference being had to the accompanying drawing, forming part thereof.

Fig. 1 is a front view of the house dress.

Fig. 2 is a back view of the house dress, one wing of the front panel being shown in a folded condition to illustrate its lap with the back panel.

Fig. 3 is a plan view of the front dress panel in extended position, shown on a reduced scale, showing the cuffs turned down and the lapels turned up.

Fig. 4 is a plan view of the rear dress panel in extended position shown on a reduced scale, showing the cuffs turned down.

I claim:

The ornamental design for a house dress, as shown and described.

EVELYN W. TURNER.
